CLAIM

The ornamental design for a molded surface of a concrete product, as shown and described.

DESCRIPTION

FIG. 1 is a front view of a molded surface of a concrete product showing our new design;

FIG. 2 is a right side view thereof;

FIG. 3 is a left side view thereof;

FIG. 4 is a top view thereof;

FIG. 5 is a bottom view thereof; and,

FIG. 6 is a perspective view thereof.

The broken lines in the drawing views are included for the purpose of illustrating portions of the molded surface of a concrete product that form no part of the claimed design.

1 Claim, 6 Drawing Sheets
